UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

HAND BRAKE.

Application filed December 14, 1922. Serial No. 606,925.

This invention relates to improvements in hand brakes for cars.

In the present practice, a common form of hand brakes employed on railway cars is that of the drop handle lever and ratchet type, in combination with a vertical staff journaled in suitable bearings. In this type of vertical staff brake and in many other types of vertical staff brakes, it frequently happens that the staff gets out of alinement with the rotating means at the top thereof, due sometimes to excessive strain on the staff and at other times to loosening of the usual lower step bearing. When this action occurs, it is obvious that there will be undue binding of the parts requiring excessive exertion upon the part of the brakeman in setting the brakes.

An object of my invention is to provide an exceedingly simple arrangement in hand brakes for railway cars, wherein the brake staff is so mounted as to prevent all binding due to bending of the staff or loosening of lower step bearing.

Another and more specific object of the invention is to provide an arrangement in hand brakes for railway cars wherein the brake staff and the ratchet member have a universal rocking connection with each other, thereby permitting a lateral rocking movement of the staff relative to the ratchet member to allow for the bending and flexing of the staff during the application of the brakes without binding.

Other objects of the invention will more clearly appear from the description and claims hereinafter following.

In the drawings forming a part of this specification, Figure 1 shows a vertical sectional view of a hand brake embodying my improvements. Fig. 2 shows a horizontal sectional view taken substantially on the line 2-2 of Fig. 1. And Fig. 3 is a top plan view of the ratchet member.

In said drawings, 10 denotes the end wall of the car to which is secured a housing or bracket designated generally by the reference character A. The latter is formed with a back wall 11 secured by rivets 12 to the end wall 10 of the car, and a horizontally extending web 13 having a bearing opening 14 therein. Said bracket is also provided with a vertically extending circular wall or web 15 and a horizontally extending

web 16 located above the wall 13 and having 55 a curved face 17.

The usual vertical brake staff is indicated at 18, it being understood that the same will have a chain winding means at its lower end receiving a chain connecting with and 60 leading to the brake rigging. At the upper end the staff 18 is formed with a square portion 19.

A ratchet member 20 having an upper and lower set of teeth 21 and 22, respectively, separated by a centrally located bearing flange 23, is journaled within the recess 14 at its reduced lower end 24. The upper end of the ratchet member 20 is reduced, as shown at 25, to co-act with a bearing on 70 the carrier member 26 hereinafter described. Operative connection between the ratchet member 20 and the brake staff for the purpose of effecting rotation of the latter is provided by means of an opening 27 in the 75 ratchet member 20 which is of substantially rectangular cross-section at all points therealong, said opening 27 extending from end to end of the ratchet member 20 and flaring uniformly in opposite directions from the center of the opening 27. By this construction, the staff will always be rotated in unison with the ratchet member 20, while allowing the staff 18 to adjust itself in substantially the manner of a universal 85 joint, with respect to the ratchet member 20, thus eliminating binding effects due to the axis of the staff getting out of alinement with the axis of the ratchet member 20. The inwardly tapering walls 26' of 90 the opening 27 are rounded at their meeting points as indicated at 27', to provide a fulcrum for the end portion 19 of the brake staff 18. The square opening 27 in the ratchet member 20 at the point 27' is of 95 slightly greater cross section than the square cross section of the upper end of the staff, thereby permitting the staff to rock freely relatively to the axis of rotation of said ratchet member without binding therein.

A carrier member 26 of generally circular outline surrounds the ratchet member 20, having bearing on the web 16 at its lower side, and provided with an upper circular bearing opening 28 adapted to receive the 105 upper reduced end portion 25 of the ratchet member. The carrier member 26 is provided with spaced side walls 29 having the

operating lever 30 pivotally mounted therebetween, on a bolt 31 extending through said walls.

The lever 30 is of well known construction, and is provided with a spring pressed pawl 32 adapted to engage with the upper set of ratchet teeth 21.

The upper end portion of the housing A is closed by a cover plate 33 held in position by a vertically extending bolt 34 passing through alined recesses in the cover plate 33, the web 16 and the web 13. On its lower face the cover plate 33 is provided with a shallow recess 134 in alinement with the ratchet member 20 to loosely accommodate the upper end of the latter.

A locking dog 35 is pivoted upon the bolt 34 between the webs 16 and 13, and has a pointed end 36 adapted to co-act with the lower set of ratchet teeth 22 to prevent retrograde movement of the ratchet member. The end 36 of the dog 35 is yieldingly held in engagement with the ratchet member by the spring 37, and the opposite end of said dog is provided with a hand lever 38 by which the same may be manipulated to disengage the dog from the ratchet member to release the brakes.

In the operation of my improved hand brakes, the lever 30 is raised from the full line position shown in Fig. 1 to the horizontal dotted line position shown in said figure, whereupon the spring pressed pawl 32 will be engaged with the ratchet teeth 21. Upon oscillating the lever 30, the ratchet member A will be intermittently rotated and through engagement with the upper square end of the brake staff 18 will rotate the latter to wind the brake chain up on the lower end thereof. In the event that the staff is bent or flexed under excessive chain pull or by reason of the usual lower step bearing becoming loosened or distorted, the lack of alignment thus caused is automatically taken care of by the universal connection between the staff and the ratchet member above described, thus minimizing the tendency to bind.

From the preceding description considered in connection with the drawing, it will be observed that the arrangement which I have provided for accomplishing the purposes

set forth, is exceedingly simple and involves no additional expense over other similar types of hand-brake mechanisms.

I have herein shown and described what I now consider the preferred manner of carrying out the invention, but the same is merely illustrative, and I contemplate all changes and modifications that come within the scope of the claims appended hereto.

I claim:

1. In a hand brake for railway cars, the combination with the wall of the car, of a brake staff journaled at one of its ends, and adapted to be mounted so as to be pulled laterally at said end, the opposite end of said staff having a portion formed polygonal in cross section; a mounting spaced from the journaled end of said staff, and secured to the car wall, and arranged to support the opposite end of said brake staff, said mounting including an operating device journaled in said mounting, said device having a polygonal bore which tapers from its ends toward a central point, at which point the walls of the bore snugly engage the related polygonal portion of said staff, said bore being arranged to permit variations in the angular displacement of said brake staff due to distortion of the staff, and to bulging of the wall of the car under strain.

2. In a hand brake, the combination with a brake staff journaled at one of its ends, and adapted to be mounted so as to be pulled laterally with reference to said end, the opposite end of said staff having an elongated portion polygonal in cross section; a stationary mounting associated with said opposite end of said staff, said mounting including an operating element journaled therein, said element having a polygonal bore substantially co-extensive with the polygonal portion of said shaft, said bore tapering from its ends toward an intermediate point where the walls of said bore snugly engage the polygonal portion of said staff.

In witness that I claim the foregoing I have hereunto subscribed my name this 26th day of October 1922.

JOHN F. O'CONNOR.
